UNITED STATES PATENT OFFICE.

FLORENCE J. OVENS, OF YORK BEACH, MAINE.

CLAM-FORK.

1,230,766.

Specification of Letters Patent. Patented June 19, 1917.

Application filed September 17, 1915. Serial No. 51,239.

To all whom it may concern:

Be it known that I, FLORENCE J. OVENS, a citizen of the United States, residing at York Beach, in the county of York and 5 State of Maine, have invented certain new and useful Improvements in Clam-Forks; and I do hereby declare the following to be a full, clear, and exact description of the invention, such as will enable others skilled 10 in the art to which it appertains to make and use the same.

The invention relates to a clam fork.

The object of the invention is to improve the construction of forks and to provide 15 a simple, practical, and comparatively inexpensive device designed for use in dining rooms and other eating places and equipped with coacting cutting blades for severing or cutting away the head of a clam 20 and provided with prongs adapted to form a fork when the instrument is closed for enabling the clam to be eaten.

With these and other objects in view the invention consists in the construction and 25 novel combination and arrangement of parts hereinafter fully described, illustrated in the accompanying drawings and pointed out in the claims hereto appended, it being understood that various changes in the form, pro- 30 portion and minor details of construction may be resorted to without departing from the spirit or sacrificing any of the advantages of the invention.

In the drawing

35 Figure 1 is a plan view of a clam fork constructed in accordance with this invention.

Fig. 2 is a side elevation of the same,

40 Fig. 3 is a transverse sectional view on the line 3—3 of Fig. 2.

In the accompanying drawing in which is illustrated the preferred embodiment of the invention, the clam fork comprises in its construction two similar members 1 45 having substantially flat intermediate portions 2 fitted against each other and pivoted by a screw, rivet 3 or other suitable fastening device and movable on each other similar to the pivoted portions of an ordinary pair of scissors to permit the members to open and close. The members are provided with handles 4 and 5 which may have openings 6 and 7 for the reception

of the thumb and fingers for enabling the members to be operated similar to an ordinary pair of scissors but the handles of the members may be of any other desired construction or design.

The members 1 are provided with blades 8 provided at the inner portions of their side edges with beveled or cutting edges 9 and having terminal prongs 10 which form a fork when the instrument is closed as illustrated in Fig. 1 of the drawing. The cutting edges 9 are arranged at an angle 65 to each other when the members are opened and closed and they are adapted to be employed for cutting away or severing the head of the clam. Each of the blades is shown in the accompanying drawing as 70 being provided with a pair of tines but the number of tines of the fork may be varied as will be readily understood and the members are preferably provided at the inner ends of the tines with a curved bend 11 for 75 extending the tines upwardly as clearly shown in Fig. 2 of the drawing. The inner edges of the handles 4 and 5 engage each other when the instrument is closed and form a stop to hold the innermost 80 prongs at the terminals of the blades in spaced relation so as to form a single unitary fork structure. The instrument is designed for use in dining rooms, restaurants and other eating places and may be made 85 plain or ornamental and of any desired material.

What is claimed is:—

1. A clam fork comprising two members having intermediate portions fitted flat 90 against each other and pivoted together, said members having handles and provided with blades having coacting cutting edges at the inner portions of their side edges, and each provided beyond the cutting 95 edges with a plurality of terminal prongs, and the prongs of both members lying in parallel planes and coacting to form a single unitary terminal fork structure when the members are closed.

2. A clam fork including two substantially similar members having flat intermediate portions pivoted together, said members having handles and provided with blades movable over each other and provided at the inner portions of their side 100 105

edges with coating cutting edges, each of said members having a plurality of terminal prongs, and said blades being curved longitudinally in parallelism to extend the 5 prongs upwardly and the prongs of both members lying in parallel planes, and forming a single unitary terminal supporting structure when the device is closed, and

means to hold the innermost prongs, at the ends of the blades in spaced relation. 10

In testimony whereof I affix my signature in presence of two witnesses.

FLORENCE J. OVENS.
